[57] **CLAIM**

The ornamental design for a manual transplanting tool, as shown and described.

DESCRIPTION

FIG. 1 is a front view of my new manual transplanting tool.

1 Claim, 7 Drawing SheetsFIG. 2 is a side view of my new manual transplanting tool. A view taken from the other side would be a mirror image thereof.

FIG. 3 is a side view of my new manual transplanting tool shown with a soil plug and plant ejector mechanism handle in a lowered position. FIGS. 1 and 2 show this handle in a raised position.

FIG. 4 is a perspective view of my new manual transplanting tool.

FIG. 5 is a top view of my new manual transplanting tool drawn to an enlarged scale than FIGS. 1, 2, and 3.

FIG. 6 is a bottom view of my new manual transplanting tool.

FIG. 7 is a bottom perspective view of my new manual transplanting tool showing a soil and transplant ejector in a raised position corresponding with a handle position as shown in FIGS. 1 and 2, with a top portion of the tool shown cut away for clarity of illustration; and,

FIG. 8 is a bottom perspective view of my new manual transplanting tool showing the soil and transplant ejector in a lowered position corresponding with a handle position as shown in FIG. 3, with a top portion of the tool shown cut away for clarity of illustration.

FIG. 1

FIG. 2

FIG. 3

FIG. 4

FIG. 5

FIG. 6

FIG. 2

FIG. 8
